UNITED STATES PATENT OFFICE.

CHARLES L. DEPOLIER, OF BROOKLYN, NEW YORK.

WATCHCASE, &c.

1,292,442.

Specification of Letters Patent.

Patented Jan. 28, 1919.

Application filed June 27, 1918. Serial No. 242,200.

To all whom it may concern:

Be it known that I, CHARLES L. DEPOLIER, a citizen of the United States, residing in the borough of Brooklyn of the city of New York, in the State of New York, have invented certain new and useful Improvements in Watchcases, &c., of which the following is a specification, reference being had to the accompanying drawing, forming a part hereof.

In Letters Patent of the United States No. 1,268,821 dated June 11, 1918, there is shown and described an improvement in watchcases which is intended and adapted to make them waterproof for a long period of time, that is, to provide means for effectually preventing the entrance of water between the members of the case, such as the center and the back and the center and the bezel. In accordance with the invention described in said Letters Patent there is provided between the proximate faces of the separable members of a watchcase an annular packing ring saturated with a water-repellent and a seat for such packing ring which has a space or recess for the reception of surplus saturant, so that the packing material shall remain always in a saturated and resilient condition and shall not become dry or hard as to its contacting face with the lapse of time. The object of the present invention is to improve further the provisions for the storage of surplus saturant, especially in watchcases in which, as ordinarily, both the back and the bezel are separable from the center which is interposed between them. In accordance with this invention, instead of forming the recess for surplus saturant as an annular groove, it is proposed to form apertures through the watchcase center, communicating on each side with the seats for the packing rings on the opposite faces of such center, thereby not only providing greater storage capacity for surplus saturant than is practically possible by the formation of grooves, but providing also for the passage of saturant from the packing ring on one side of the center to the packing ring on the other side so that the saturant will at all times be equally distributed between the two packing rings, notwithstanding

the fact that one of said packing rings may be exposed more frequently than the other, as, for example, through the more frequent removal of the bezel or the back of the case and notwithstanding the fact that there may be a difference in the quality of the two packing rings. The invention will be more fully explained hereinafter with reference to the accompanying drawing in which it is illustrated and in which—

Figure 1 is a face view of a watch to which the invention may be applied.

Fig. 2 is a face view, on a larger scale, of the watchcase center constructed in accordance with the invention.

Fig. 3 is a detail view in section on the plane indicated by the broken line 3—3 of Fig. 1, but on a larger scale.

In the embodiment of the invention illustrated in the drawing the back *b* and the bezel *c* have respectively, as indicated at *b'* and *c'*, a screw-threaded engagement with the center *a*. The back *b* and the bezel *c* may also be formed, as at *b²* and *c²* respectively, with an annular seat adapted to receive a ring *d* of suitable backing material. The center *a* is also provided, on each side, with an annular seat *a'* to receive the corresponding ring *d* of packing material, each seat being preferably dove-tailed so as to retain the packing ring in place when the back or bezel, as the case may be, is removed. In the web *a²* between the two faces of the center are formed, at suitable intervals, apertures *a³* which extend from face to face of the web. These apertures may be of substantial size and they form, therefore, ample storage space for the surplus of the saturant with which the packing rings are charged. Moreover, as the quality of the two packing rings may differ somewhat and as one packing ring may be exposed more frequently than the other, these apertures permit the surplus saturant to pass from one packing ring to the other, whereby the saturant is at all times equalized between the two packing rings and both are at all times kept equally soft and resilient.

I claim as my invention:

A watchcase having a center, a separable back and a separable bezel and provided

with an annular seat for packing material between proximate faces of the separable members and with saturated packing between the proximate faces, the web of the 5 center, between the seats for the packing, being formed with apertures to constitute

storage space for surplus saturant and to permit the saturant to pass from one side of the web to the other.

This specification signed this 24th day 10 of June, A. D. 1918.

CHAS. L. DEPOLLIER.
